UNITED STATES PATENT OFFICE.

ARTHUR R. PETERSON, OF SAN FRANCISCO, CALIFORNIA.

BILLIARD-CUE-CHALKING DEVICE.

Application filed November 30, 1925. Serial No. 72,077.

This invention relates to billiard-cue chalking devices, and has for its primary object the provision of a device adapted to automatically chalk a cue upon the insertion of the cue tip into a rifled barrel, the chalk being carried by a spring-pressed follower, said follower being provided with means for engaging the barrel rifling to cause a partial rotation of the chalk against the cue tip upon pressure or thrust being imparted to the cue, and the release of this pressure permitting the return of the follower and chalk to normal position, the cue tip receiving a coating of chalk upon both the forward thrust and return movement of the follower.

Another object of the invention is the provision of a cue chalker of simple and attractive design, cheaply manufactured, of economical operation, and of a character that will prevent players inadvertently carrying off the chalk.

Other objects and advantages will appear with reference to the subjoined specification and accompanying one sheet of drawings, in which:

Figure 1 is a perspective view of my cue-chalker, as it would appear attached to a supporting object in readiness for use, the barrel being adjustable to any angle, relative to the supporting bracket;

Figure 2 is a longitudinal mid-section of the device, showing the spring and follower in normal position and the chalk in readiness for use; the section being taken as indicated by the line 2-2 of Figure 3;

Figure 3 is a fragmentary end view of the device, showing the method of rifling the barrel, and the corresponding projections formed upon the periphery of the follower;

Figure 4 is a perspective view of the follower, showing the chalk-gripping recess formed in the outer end thereof; and the spirally arranged projections carried thereby and adapted to travel in the barrel rifling to cause the partial rotation of the follower when thrust into or retracted in the barrel; and

Figure 5 is a sectional detail of the supporting lug and hinge-ears carried by the barrel, both being provided with serrations upon their contacting faces to rigidly hold the barrel at any desired angle relative to the supporting bracket.

Referring with greater particularity to

the drawings, 1 designates the barrel of the device, which is preferably die-cast of aluminum or other light metal, the barrel being provided with a finished bore 2, open 60 at its outer end and closed at its inner end 3. The outer end of the barrel is exteriorly screw-threaded, as indicated at 4, and provided with an interiorly screw-threaded cap 5, said cap being provided with an inwardly extending lip 6, concentrically disposed relative to the barrel and cap, and a centrally disposed outwardly flared opening 7 adapted to receive and guide the cue tip to the chalk 8 which is held spring-seated 70 upon the lip 6 within the barrel end.

A follower 9 is provided having an exterior diameter slightly smaller than that of the bore 2 of the barrel, adapting it to form a sliding fit therein, the inner end of 75 the follower being recessed, as indicated at 10, and provided with a centrally positioned member 11 upon which a bearing washer 12 is seated, said washer being adapted to provide a bearing for the expansion spring 13, 80 providing a means against which the follower member 9 may rotate when forced longitudinally, in either direction, along the barrel.

The spring 13 is seated in the recess 10 85 of the follower and is of somewhat smaller diameter than that of the barrel bore 2 and extends between the washer 12 and upper end 3 of the barrel, the spring urge tending to normally hold the follower in the outer 90 end of the barrel, with the chalk 8 seated upon the lip 6 of the cap 5, as shown in Figure 2.

The bore 2 of the barrel is grooved, or rifled, from its outer end rearwardly, the rifling extending approximately half the length of the barrel, with the rifles, or grooves, 14 and 15 arranged in diametrical opposition; Figures 2 and 3, and in reversed spiral directions, as shown in Figure 2.

The follower 9 is provided with peripherally arranged and diametrically disposed lugs 16 and 17 extending spirally thereabout in reversed order and of a depth and form to fit loosely in the grooves 14 and 15 of the barrel, in which they are adapted to travel and, therethrough, rotate the follower 9, a thrust inwardly to the limit of travel accomplishing, approximately, a one-half rotation of this chalk-bearing member.

A spirally arranged groove 18 is formed

in the outer surface of the follower and terminates adjacent the inner end thereof, said groove corresponding in pitch to that of the groove 14 and adapted to prevent the complete ejection of the follower, through engagement with a small screw 19, tapped into the barrel wall and extending into the bore of the barrel far enough to engage in the groove 18, but not to a sufficient depth to prevent the complete rotative action of the follower.

Normally the follower is held slightly within the end of the barrel by the cue chalk 8, which is held seated upon the lip 6 of the cap by the spring 13. When necessary to insert a new piece of chalk in the follower, the cap is removed, the follower being held from ejection by the screw 19 engaging the inner end of the groove 18. The outer end of the follower is provided with a rectangular recess 20 of sufficient size to accommodate the ordinary cube form of chalk, but, that it may also accommodate that of cylindrical form, arcuate sections 25 are removed from the sides of the said recess, as represented by 21, Figure 4, these features contributing to the prevention of rotation of the chalk in the follower.

The barrel is provided at its inner end with integrally formed hinge-ears 22 and 23 adapted to embrace a supporting lug 24 integrally formed with a supporting plate 25, the said ears and lug bearing openings adapted to accommodate a hinge bolt 26 having a head at one end and a nut 27 adapted to be drawn up tightly to set and retain the barrel 1 at any desired angle relative to the supporting plate, the inner faces of the hinge-ears and the outer faces of the lug 24 being correspondingly serrated, as indicated at 28 and 29, as interlocking aids to permanency of position of the barrel, once these members have been tightly drawn together by setting up the nut 27. The supporting plate may be properly secured in any convenient position by means of screws 30 and 31. The member 11 of the follower and the end 3 of the barrel are provided with perforations 32 and 33, as means affording relief against air-pressure.

The outer face of the member 11, against which the chalk 8 rests, is provided with a plurality of radially extending ribs 34, adapted to assist in holding the chalk 55 against tendency to rotate, relative to the follower 9.

Having thus described my invention, I claim, and desire to secure by Letters Patent:

1. A billiard-cue chalker comprising a barrel, a supporting bracket therefor comprising a member adapted for hinged connection to said barrel, a bore extending longitudinally of said barrel and provided with a pair of reversely arranged rifles or grooves and of diametrically opposite disposition, a follower adapted for longitudinal and rotary movement in said barrel bore and provided with peripherally placed lugs adapted to fit and travel in said grooves, a spring in said bore between the inner end of the barrel and said follower and adapted to normally hold said follower in the outer end of the barrel bore, a recess in the outer end of the follower adapted to hold a piece of cue chalk, a peripheral groove carried by said follower adapted to engage a screw borne by the barrel wall for preventing the complete ejection of said follower from the barrel bore, and means for normally holding said follower and chalk slightly within the end of the end of the barrel bore.

2. A billiard-cue chalker comprising in combination, a supporting bracket, a barrel hingedly secured to said bracket and adapted for angular adjustment relative thereto, a retaining cap having a flared opening and lip secured to the outer end of said barrel, a bore extending longitudinally of said barrel and provided with a pair of reversely arranged spiral rifles or grooves of diametrically opposed disposition, a follower adapted for longitudinal and rotary movement in said barrel bore and provided with peripherally arranged lugs adapted to fit and travel in said grooves, a spring in the barrel bore between the follower and the inner end of the barrel and adapted to urge said follower toward the open end of the barrel, a chalk recess in said follower adapted to grip and hold the chalk, said spring acting to normally hold the chalk seated against said retaining cap-lip in position for use, and a peripheral groove carried by said follower and adapted to engage means projecting inwardly from the barrel wall for preventing the complete ejection of said follower from the barrel bore.

In testimony whereof I have affixed my signature.

ARTHUR R. PETERSON.
